UNITED STATES PATENT OFFICE.

BEN C. GERWICK, OF BERKELEY, CALIFORNIA.

COFFER AND METHOD OF MAKING THE SAME.

Application filed February 20, 1924. Serial No. 694,001.

The invention relates to a coffer or other subaqueous structure for excluding water and other materials from a confined area. The invention also relates to a method of 5 making large coffers.

It has been the practice heretofore, in building piers and other structures in water or in flowing mud, to use the plenum air or pneumatic caisson or to sink a surrounding open caisson, crib or cofferdam of earth, timber, steel, concrete, or combinations of these materials, to exclude water and other materials from the surrounded space, to permit the structure within the space to be 15 built. The pneumatic system of operation is expensive, is detrimental to the health of the workmen and is of such character, that where wooden piles have to be driven to form the foundation for the structure, almost insurmountable difficulties are met. 20 The pneumatic system also limits the depth to which the structure may be carried, due to the air pressure which can be sustained by the workmen. Open cribs, caissons and 25 cofferdams have heretofore presented many troubles of bracing and unwatering, it being practically impossible to make the open cofferdams sufficiently tight so that they may be unwatered to any great depth.

30 When the structure to be built is large, requiring a large cofferdam or caisson, the weight of such caisson or cofferdam is so great that it cannot be handled. This is particularly true when the structure is to be 35 built in shallow water overlying deep mud, the shallowness of the water precluding floating a caisson or crib into place. Currents and tidal flow also present obstacles to the floating of a pre-cast or pre-built 40 crib or caisson into place and also interfere with the maintaining of alignment of the caisson, as it is being sunk.

An object of the present invention is to provide a coffer which overcomes the above 45 mentioned difficulties and which may be built in any desired size to enclose any desired area.

Another object of the invention is to provide a coffer which possesses inherent resistance to external pressure, so that the 50 necessity of internal bracing is eliminated.

Another object of the invention is to provide a method of building a large coffer whereby no unusual or large weights require handling or lifting.

A further object of the invention is to

provide a method of building a large coffer in vertical sections.

The invention possesses other advantageous features, some of which, with the foregoing, will be set forth at length in the following description, where I shall outline in full that form of my invention which I have selected for illustration in the drawings accompanying and forming part of the present specification. In said drawings I have shown one form of coffer embodying my invention and in the specification I have described one method of making the coffer, but it is to be understood that I do not 60 limit myself to such form or method, since the invention, as set forth in the claims, may be embodied in a plurality of forms and constructed by a plurality of methods.

Referring to said drawings:

Figure 1 is a vertical section through the completed coffer of my invention, showing one form of structure arranged within the coffer.

Figure 2 is a top or plan view of the 80 completed coffer and structure shown in Figure 1.

Figure 3 is a detail of one of the concrete shafts forming part of the coffer, a portion of the shaft being broken away to disclose 85 the anchor for one of the walls connecting two adjacent shafts.

Figure 4 is a detail of a portion of the coffer showing various parts of the coffer in different stages of construction.

The coffer of my invention comprises generally a plurality of spaced concrete shafts built in situ and extending from above the water line to the established grade. The shafts are connected together by concrete walls built in situ, which close the spaces between the shafts, thus forming an integral structure in which the shafts may be considered as abutments for receiving the strain placed on the walls. The centers 95 of the shafts are preferably arranged on a curve, usually a circle, so that the line of shafts surround the area to be unwatered. The walls connecting the successive shafts are also preferably curved and, when the 100 shafts are arranged in a circle, the walls are concentric with the center of the circle. When the shafts are arranged in a straight line, the walls are curved to form arches, so that the stresses applied to the walls are 105 transferred to the shafts, which act as abutments. It is not necessary that the shafts be 110

arranged in a circle since, when the coffer is to enclose an area, the coffer may be elliptical or otherwise curved. The walls present their convex face to the surrounding water and mud which is held back by the coffer, and by completely surrounding the area with the coffer, the coffer is self-supporting, and requires no internal bracing.

I prefer to build the coffer in successive vertical sections, progressing around the area to be enclosed, so that no large or unusual weights are required to be handled. In carrying out the invention, a steel cylinder or shell 2 is set in position and sunk 10 to the established grade, either by digging out the interior or by driving the shell. The upper edge of the shell extends above the water line, when the shell has been sunk to the established grade, so that water will not 15 enter the shell. After the shell has been sunk to the established grade, the mud, sand or other material within the shell is removed and a base 4 is then formed in the bottom of the shell. When desirable, piles 5 may 20 first be driven before the base is placed and these wooden piles 5 may readily be driven in the bottom of the cylinder by using extension leads on the pile driver. The concrete base 4 is then formed, either by placing 25 the concrete under water with a tremie, or by first unwatering the cylinder and placing the concrete in the usual manner. After the base has been formed a shaft form 6 is 30 arranged within the cylinder and preferably 35 concentric therewith, and concrete is poured into the form 6 to produce the concrete shaft 7. The successive shafts, after they have 40 been formed and after the cylinders 2 have been removed, are connected together successively by a pair of spaced walls 8 formed of 45 sheet steel piling 9. The forms 6 are provided on opposite sides, adjacent the successive shafts, with anchors 12, extending through the forms and adapted to receive the sheet steel piling which is to be driven 50 to form the walls. Sheet steel piling usually has one male edge and one female edge, the two edges being interlocked by driving the piling and one of the anchors is preferably provided with a male edge and the anchors on the other side of the shaft with female edges. These anchors are usually formed by cutting a sheet steel pile in half longitudinally on a tortuous line and the cut 55 portions of the pile extend through the form 6 into the interior thereof where they are secured to reinforcing 13 within the form, which reinforcement is shown as secured to vertical reinforcing rods 13a. After the 60 concrete has been poured into the form, the anchors are solidly and rigidly held.

After the shaft 7 has been formed and set, the form 6 is removed and the cylinder 2 is 65 lifted from position and advanced to another position where it is again sunk for the

purpose of forming another shaft. The shafts are formed successively, following around the curve of the coffer, and after all of the shafts have been completed and the cylinders withdrawn, the sheet steel piling 9 is driven to confine the spaces between the successive shafts. The mud, sand or other material contained in these spaces is then removed and the space is then completely filled to any desired elevation with concrete, 70 which may be placed in any desirable manner. The concrete may be placed with a tremie, without unwatering the confined space, or a canvas stocking of the size and shape of the confined space may be fitted into the space and the concrete poured into the stocking, which would prevent washing out of the concrete. These walls are built up to a point above the water level and when they have been completed, there is produced a great concrete cylinder which has been built up under water in vertical sections and which forms a stable, watertight coffer. The area within the coffer is then excavated to the desired grade and, the bottom of the area may be sealed with concrete placed with a tremie, before the water is pumped out. Any desirable structure may now be built within the coffer and, when it is desired, the coffer may form part of the structure. 90

The invention of course is not limited to a coffer having walls formed in a cylindrical shape since it is obvious that the invention may be applied to a coffer having inclined walls or a coffer in which the walls are not curved but form straight sides which are joined together to inclose a given area. The walls 14, connecting the shafts, are preferably curved on the same curve of the axis of the shafts, but this is not necessary, since when desired the connecting walls may be given any desired curvature to meet the requirements of the situation. When it is desired, piles 16 may be driven in the confined area within the coffer, before the sealing layer of concrete is placed therein. 100

I claim:

1. A coffer comprising a plurality of spaced concrete shafts formed in situ and surrounding the area to be dewatered, a pair of elongated vertically disposed anchors projecting from each side of each shaft, sheet steel piling connecting the anchors on one side of each shaft with the anchors on the adjacent side of the next shaft whereby the shafts are connected by a pair of spaced walls and a filling of concrete in the spaces enclosed by the walls. 115

2. The method of building a coffer which comprises sinking a shell to the established grade, removing the material from the interior of the shell, placing a shaft form in the shell, filling the form with concrete, forming a second shaft in the same manner, confining a space between the two shafts, 120

removing the material from the confined space and filling the space with concrete.

3. The method of building a coffer which comprises sinking a shell to the established grade, removing the material from the interior of the shell, placing a shaft form in the shell, filling the form with concrete, removing the shell, forming a second shaft in the same manner, removing the forms from the shafts, confining a space between the shafts, removing the material from the space and filling the space with concrete.

4. The method of forming a coffer wall comprising, forming spaced concrete shafts in situ and embedding two pair of attach-

ing members in the concrete of each shaft, positioning sheet piling in two rows between said shafts and connecting the same to corresponding attaching members, and filling in the space between adjacent shafts 20 to form substantially a continuous wall.

5. The method of forming a subaqueous wall comprising forming a concrete shaft in situ and embedding a pair of anchoring members embedded in the concrete, attaching form members to said anchoring members, and filling the forms with concrete.

In testimony whereof I have hereunto set my hand.

BEN C. GERWICK.
